COMBINATION SOCK AND ANKLET

Application filed August 9, 1932. Serial No. 628,100.

This invention relates to wearing apparel and particularly to an improved combination sock and anklet, the object being to provide a construction which may be worn by any one but which is designed to be used by children, the structure permitting an adjustment which is particularly pleasing to children.

Another object of the invention is to provide an improved construction wherein the parts may be adjusted to present a sock having a cuff which will not slide down or wrinkle.

Another object of the invention is to provide an improved article of footwear in the nature of a sock which may be used as a sock having a cuff or may be adjusted to present a sock structure having an anklet either with or without ornamental members on the cuff and on the anklet.

In the accompanying drawing—

Figure 1 is a side view of the combined sock and anklet disclosing an embodiment of the invention;

Figure 2 is a vertical sectional view through the upper part of the structure shown in Figure 1;

Figure 3 is a view similar to Figure 1 but showing the parts adjusted to present a sock with an anklet;

Figure 4 is a vertical sectional view through the upper part of the structure shown in Figure 3.

Referring to the accompanying drawing by numerals, 1 indicates the foot of a sock which merges into a very short ankle extension 2, and this ankle extension 2 merges into a top structure 3 which may be adjusted to present a cuff 4, as illustrated in Figures 1 and 2, or may be adjusted to present an anklet 5, as shown in Figures 3 and 4.

The portion 2 is very short and in knitting the cuff 4 it is knitted double length and then turned in and stitched in place by the line of stitching 6. The cuff 4 is of the ribbed type and, consequently, will hug rather close the upper ankle of the person wearing the sock so that it will not crumple or slide down as half length socks or stockings will.

In order to be pleasing to children the

cuff 4 is provided with an ornament 7 which is knit into the goods in a known manner, and preferably provided on both sides so that the cuff 4 will have the same appearance on both sides. In addition an ornamental structure 8 is knit on the interior layer 4', but which is naturally hidden when the cuff is being used. However, when the cuff 4 is turned to present an anklet, as shown in Figure 3, the ornamental structure 8 will be arranged exteriorly and will give a pleasing appearance. This ornamental structure may be the same interiorly as exteriorly, or different, as preferred. It will be understood, of course, that a wide number of designs can be used exteriorly or interiorly as desired without departing from the spirit of the invention, but usually an ornament is provided on each structure so as to present a pleasing and finished appearance both to the cuff when used as such, and to the anklet when used as such.

When in either position the action of the ribbed portion extending from the line of stitching 6 to the top of the garment is such that it will snugly fit the leg of the wearer and not slide down, as is customary when half-length stockings are worn. Also, there is no seam or ragged edge ever presented to view.

What is claimed is—

A combined sock and anklet comprising a foot merging into an ankle section, said ankle section being folded upon itself, the folded portion extending interiorly and downwardly toward the foot to present a cuff having a finished surface interiorly and exteriorly, a line of stitching for holding the folded portion in its permanent position, ornamental members arranged exteriorly of said cuff, and ornamental members arranged interiorly of the cuff on the folded part in the space between the top of the cuff and a central line, whereby when the cuff is extended the outside ornamental member will be seen and when the cuff is folded along the central line to present an anklet the inside ornamental member will be seen arranged substantially centrally of the cuff.
